UNITED STATES PATENT OFFICE.

S. L. CROCKETT AND BENJAMIN T. MILLS, OF LOWELL, MASSACHUSETTS.

IMPROVEMENT IN MACHINES FOR STRIPPING THE TOP FLATS OF CARDING-ENGINES.

Specification forming part of Letters Patent No. 58,989, dated October 23, 1866.

To all whom it may concern:

Be it known that we, SELDON L. CROCKETT and BENJAMIN T. MILLS, both of Lowell, in the county of Middlesex and State of Massachusetts, have invented a new and useful Improvement in Machinery which is used for Stripping the Top Flats of Carding-Engines; of which the following is a full, clear, and exact description, reference being had to the accompanying drawings, making part of this specification, in which—

Figure 1 is an end elevation of a carding-engine which has a stripping apparatus applied thereto. Fig. 2 is a side view of the same. Fig. 3 shows the working side of our improved lifting and replacing cam, with the position of the stripper-arm F and yoke T as shown in red lines. Fig. 4 shows a vertical central section of the stripper-arm F, the cam W, the movable slide h, and lifting-pins 1 and 2, one guide-pin, i, a portion of one top flat, b, and a lifting-jaw, k, all of which pertain to the said carding-engine. Fig. 5 shows the working side of one of our improved cams, full size, for practice with the lifting-pins in different positions around the grooves of the cam. Fig. 6 is a central section of said cam. Fig. 7 is a plan, and Fig. 8 a vertical central section, of one of the movable slides, with the lifting-pins connected therewith. Fig. 9 is a side view of a lifting-jaw.

Our invention consists in the employment of a lifting and replacing cam, so formed and arranged as to lift the top flats of carding-engines, perform a positive depression of said top flats onto the strip-card, and replace them in their proper positions without the aid of depressing-springs or other similar device arranged to bear the top flats down when the stripping is performed; and the said cam may be turned backward as well as forward without breaking or injuring any of the machinery.

The card-cylinder A rotates on bearings at the center of the top girts B of the frame, which are supported by posts C at each corner. A metallic arch, D, is secured by bolts through the feet a of the arch to the top girts B. The top flats b are arranged on the outer surface of these arches, and are movable from and toward the center of the shaft E of the cylinder A, upon which shaft stripper-arms F, at each side of the engine, are made to move at

intervals forward and back by means of a gear, e, working into a mangle-pin segment, G, secured to the outside of each of the arches D.

The gear e receives motion from a segmental gear, H, on the outer surface of the cam W, (shown in Fig. 1,) through the tumbler-gear d, secured to the same shaft.

The segmental gear-cam and full gear J are driven by an intermediate gear, e, connected with another intermediate gear, f, which receives its motion from the gear g, on either end of the top shaft, H; and a belt running from the pulley M, on the shaft E of the cylinder A, onto the pulley L, on the top shaft, H, drives the whole stripping apparatus.

In the machinery for stripping the top flats of carding-engines patented by George Wellman, of Lowell, Massachusetts, January 27, 1857, all of the above-described apparatus is used, and the said Wellman employs a lifting and replacing cam consisting of several detached flanges or projections cast upon the surface of a plate. Said flanges are made to operate a slide having four pins secured thereto. Three of the pins are acted upon by the detached flanges to lift and replace the top flats, and a spring secured to the under side of the cross-stay m on the top ends of the stripper-arms F is designed to depress the top flats onto the stripper-card and cause it to strip the top flats clean. The fourth pin on the slide is intended to guide the first or outer pin outside of one of the detached flanges in replacing the top flats, but the outer pin sometimes passes inside of the said flange, and then the flange or pins are broken. This cam, having detached flanges, can turn only one way, and in the attempt of unpracticed operators to turn the stripper back, in order to strip the main cylinder, the detached flanges are frequently broken off, which spoils the whole cam, so that a lifting-cam, stripping-cam, and gear have to be replaced, being all connected.

In the drawings, Fig. 5 represents the precise form of our improved cam, with the two lifting-pins 1 and 2 in different positions around in the grooves R and P of said cam, as indicated by Figs. 1', 2', 3', to 8'.

Our cam begins to lift the top flat on pin 1, in position 1', and as said pin moves outward on the continuous flange 13 the pin 2 passes

inside of a prominent point, 66, and catches on the point 14 of the inner flange, N. Pin 1 passes outside of and above the edge of the cam, and pin 2 around in the groove P, and when the lifting-pin 2 passes from position 4' to 5' said pin is moved downward by the offset y, forcing the slide, jaw, and one top flat with which the jaw is engaged down onto the strip-card, thus performing a positive depression of the top flat at each stripping operation.

Sufficient time is had, while the pin 2 is passing from the offset y to the point 15 on the flange N of the cam, for the strip-card to be withdrawn from beneath the top flat, and said flat begins to fall as pin 2 passes point 15, and continues to fall until pins 1 and 2 are nearly to that point indicated by position 8', from which point or position to position 1' the stripping device is moving from one top flat to another.

In order to strip the main cylinder A, it is frequently necessary to lose considerable time in waiting for the apparatus to work its way over to one side of the engine; but by the use of our improved cam the stripping apparatus can be moved backward by reversing the motion of the cam and turning the stripper back to the point desired, without injuring the cam or the lifting-pins, or any part of the machinery, as the peculiar form of said cam admits of its being turned backward quite as easily as forward.

Forming our improved cam with grooves R and P and continuous flanges O, S, and N precludes the possibility of the lifting-pins 1 and 2 getting out of place.

All the curves of our improved cam are important and cannot well be changed, and some

prominent points and curves cannot be changed at all without spoiling the operation of the cam. The point 22 on the outer portion of the double flange S, and the point 66 on the inner portion of the opposite end of said flange, the point 33 on one extremity of the flange O, and the point 44 on one extremity of the flange N are absolutely necessary in reversing the motion of the cam to turn the stripper backward. The point 55 on one extremity of the flange O guides the pin 1 properly in replacing the top flats after the stripping has been performed, and, making that portion of the flange S between 10 and 10 continuous, is also necessary, to guide the pin 1 past the point 22, and prevent the pins 1 and 2 dropping too suddenly or in any way getting out of place.

We do not claim the machinery for stripping the top flats of carding-engines, nor the lifting cam or cams used by George Wellman or Horace Woodman; but

We do claim as follows:

1. In the machinery which is used for stripping the top flats of carding-engines, the employment of the lifting and replacing cam, formed substantially as herein set forth and shown, and arranged to operate in the manner and for the purpose specified.

2. In combination with the lifting and replacing cam, formed and made to operate as herein set forth, the two pins 1 and 2 in the slide h, acted upon by the cam in the manner and for the purpose specified.

SELDON L. CROCKETT.
BENJAMIN T. MILLS.

In presence of—

JOHN E. CRANE,
J. S. WHITNEY.
